US00D804147S

(12) United States Design Patent (10) Patent No.: US D804,147 S
Geishauser et al. (45) Date of Patent: * Dec. 5, 2017

(54) POCKET FOR PANTS' LEGS

(71) Applicants: Clair M. Geishauser, San Antonio, TX (US); Theresa A. Lyon, Toledo, IA (US); Tyrel J. Lyon, Abilene, TX (US)

(72) Inventors: Clair M. Geishauser, San Antonio, TX (US); Theresa A. Lyon, Toledo, IA (US); Tyrel J. Lyon, Abilene, TX (US)

(73) Assignee: Clair M. Geishauser, San Antonio, TX (US)

() Term: 15 Years

(21) Appl. No.: 29/553,182

(22) Filed: Jan. 29, 2016

Related U.S. Application Data

(62) Division of application No. 29/485,946, filed on Mar. 25, 2014, now Pat. No. Des. 792,681.

(57) CLAIM

The ornamental design for a pocket for pants' legs, substantially as shown and described.

DESCRIPTION

FIG. 1 is a side view of the first embodiment of the pocket for pants' legs with a flap showing my new design.

FIG. 2 is a side view of the second embodiment of the pocket for pants' legs with a flap and an interior pocket; and, FIG. 3 is a sectional view of flap of the pocket for pants' legs with a flap of FIG. 1.

The dot-dash broken line immediately adjacent the shaded areas represent the bounds of the claimed design, while all other broken lines are included for the purpose of illustrating the portions of the pants and such broken lines forming no part of the claimed design.
